ELECTRIC BOOT DRIER

Rudolph Charles Schramm, Toledo, Ohio
Application June 8, 1953, Serial No. 360,087

4 Claims. (Cl. 212—19)

This invention relates generally to devices for drying boots and pertains more particularly to an improved form of such devices utilizing electricity in its operation.

The primary object of this invention is to provide an improved form of electric drier which is simple yet effective in construction and lends itself readily to economical mass production.

Another object of this invention is to provide an extremely efficient design of electric boot drier having a removable electric heating unit therein.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the boot drier showing the same in position for use within an associated boot, the boot being shown in dotted lines;

Figure 2 is a vertical section taken substantially along the plane of the section line 2—2 of Figure 1;

Figure 3 is a horizontal section taken substantially along the plane of section line 3—3 of Figure 1 showing details of internal construction of the device on enlarged scale; and

Figure 4 is a perspective view of the removable heating unit.

Referring now more particularly to the drawings, reference numeral 10 indicates a guide ring forming a part of this invention which is adapted to be placed within the interior of a boot 12 to space the assembly in proper relation therein. The guide ring is of circular configuration as shown and is provided with the screen or foraminous material 12 for a purpose presently apparent. A rectangular member 14 is secured to the screen 12 and is provided with vertically disposed corner posts 16 extending therefrom which corner posts are provided with the screen or mesh 18 to provide a foraminous enclosure within which the heating unit as indicated generally by the reference character 20 is disposed. The L-shaped guide rods 22 are secured at their lower laterally bent ends 24 to the frame 14 and extend vertically within the foraminous enclosure to a point substantially flush with the top thereof to which the support ring 26 and its associated screen 28 are rigidly secured by any suitable means. The heating unit includes a pair of spaced vertical frame members 30 and 32 of tubular construction which are adapted to engage over the guide rods 22 in the manner shown and the upper ends of these tubes are secured to the cover plate 34 having the insulating plate 36 and associated prongs 38 secured thereto. The insulating blocks 40 and 42 extend between the tubular frame members 30 and 32 in the manner shown and are apertured adjacent their opposite ends for reception of the loop of coiled resistance wire 44 whose opposite ends are secured to the plug member 38. Peripheral portions of the cover plate 34 are adapted to overlie and be supported upon the rectangular flange member 46 which is secured to the upper ends of the corner posts 16.

Diametrically opposed points on the support ring 26 are provided with the bracket ears 48 which are apertured to receive the opposite looped ends 50 of the U-shaped handle member 52 whose main portion thereof is provided with the resilient cover 54.

When it is desired to utilize the drier, the assembly is placed within a boot to be dried in the manner indicated in Figure 1 with the guide ring 10 engaging the inner sur-

2

face thereof and spacing the assembly in proper position relative thereto with the support ring 26 also engaging the inner surface of the boot adjacent its top, it being appreciated that the frictional contact of the support ring

5 with the inner surface of the boot will be sufficient to maintain the drier in the position desired. A suitable household electric current outlet female plug is associated with the prongs 38 to heat the resistance wire 44 so that the interior of the boot may be heated and accordingly 10 dried, the foraminous material allowing free circulation of air throughout the interior of the boot and allowing the radiation from the heating coil to most effectively dry the same.

It will be manifest that the electric heating unit may 15 be easily and quickly removed from the remainder of the drier assembly and replaced or repaired as necessary.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. An electric boot drier comprising lower and upper guide members adapted to be positioned within a boot to be dried, a foraminous frame interconnecting said lower and upper guide members, a removable electric heating unit supported in insulated relationship within said frame, and vertical guide rods extending upwardly from said lower member, said heating unit including tubular leg portions removably receiving said rods.

30 2. An electric boot drier comprising a lower guide ring adapted to be disposed within a boot, a pair of guide rods extending upwardly from said ring, a removable electric heating unit including a pair of tubular frame members telescopically removably receiving said guide rods, insulator blocks secured between said frame members, and an electric resistance coil carried by said insulator blocks.

35 3. An electric boot drier comprising a lower guide ring adapted to be disposed within a boot, a pair of guide rods extending upwardly from said ring, an electric heating unit including a pair of tubular frame members telescopically receiving said guide rods, insulator blocks secured between said frame members, an electric resistance coil carried by said insulator blocks, a foraminous housing surrounding said heating unit and secured to said guide ring, and a support ring secured to the upper end of said housing for supporting the heating unit therein.

40 4. An electric boot drier comprising a lower guide ring adapted to be disposed within a boot, a pair of guide rods extending upwardly from said ring, an electric heating unit including a pair of tubular frame members telescopically receiving said guide rods, insulator blocks secured between said frame members, an electric resistance coil carried by said insulator blocks, a foraminous housing surrounding said heating unit and secured to said guide ring, a support ring secured to the upper end of said housing for supporting the heating unit therein, and a U-shaped handle secured to said support ring.
